US0D1036880S

(12) United States Design Patent (10) Patent No.: US D1,036,880 S
(45) Date of Patent:  Jul. 30, 2024

(54) CHANGING TABLE FOR BABIES

(71) Applicant: STOKKE AS, Ålesund (NO)

(72) Inventors: Hans-Cato Slotterøy, Ålesund (NO);
Anders August Kittelsen, Ålesund (NO);
Sofia Ohlsson, Ålesund (NO)

(73) Assignee: STOKKE AS, Ålesund (NO)

() Term: 15 Years

(21) Appl. No.: 35/517,107

(22) Filed: May 12, 2022

(80) Hague Agreement Data

Int. Filing Date: May 12, 2022

Int. Reg. No.: DM/220889

Int. Reg. Date: May 12, 2022

Int. Reg. Pub. Date: May 12, 2023
